UNITED STATES PATENT OFFICE.

CHARLES L. LAWRENCE, OF NEW YORK, N. Y.

TOOL KIT.

Application filed January 24, 1925. Serial No. 4,409.

My invention relates particularly to kits for the use of mechanics, and the main object is to provide a simple, strong, and inexpensive construction by which a miscellaneous kit of tools can be conveniently packed and carried. I have particularly sought to design a kit convenient for automobile mechanics who require sets of wrenches for nuts and cap screws.

10 Fig. 1 is a longitudinal sectional view and side elevation of a kit embodying a carrying case and a removable tray, the cover being shown closed.

Fig. 2 is a transverse sectional view showing the cover open, parts of the tray being broken away and the handle of the tray being shown dotted in its raised position.

Fig. 3 is a plan view of the tray, part of the handle being broken away.

20 The case 5 may be of any suitable construction, preferably provided with a hinged cover 6 and one or more catches or locks 7. The bottom of the case is preferably provided with protuberances 8, serving as casters 25 to facilitate the sliding of the case on the floor or bench. The case is also preferably provided with some suitable form of handle 9.

The tray 10 may be of any suitable material such as sheet metal and provided with bosses or protuberances 11 serving as casters or supporting feet. The central part of the tray is provided with a series of compartments formed by side walls 12, transverse partitions 13 and 14, and other side walls 15 and 17 and transverse partitions 16 and 18. The transverse partitions 13 and 14 divide up the space between the walls 12—12 into two oppositely disposed series of compartments such as 19, graded in depth from the center toward opposite ends, those near the center being deepest and those near the ends being shallowest so as to accommodate two series of nut and bolt wrenches. The walls 15 and 17 are lower than the walls 12 so that the compartments formed between them and the walls 12 are shallower to accommodate the shorter wrenches. Other compartments 20 may be provided at opposite ends of the central graded wrench compartments for the accommodation of small articles or tools. Preferably I provide slots in the walls 12 at the edges of the compartments so as to facilitate the introduction of some small tool, such as a screw-driver or wire, for the purpose of fishing out short

wrenches which may be accidentally dropped into the deeper compartments and which would otherwise be very difficult to reach.

To facilitate lifting the tray within the case and carrying it about, I preferably provide a handle such as 22 which may be vertically adjustable so that it will take up a minimum amount of room when in the case but so that it may be more conveniently 60 grasped for carrying the tray around. This handle may also be guided by pins or lugs 24 to prevent it from tipping over. It will be noted that the carrier is so designed that the longer and heavier wrenches are located 65 near the center. This gives much more central distribution of the weight and consequently better balance.

In the cover of the case I may also provide one or more compartments or drawers 75 such as 25 guided by plates 26 and provided with a handle or finger-piece, such as 27 or 28. These drawers are spaced apart from each other so as to leave space enough between for the drawers to be operated and 80 also so as to leave space for the handle and the upper ends of the longer wrenches when the cover is closed.

The case is also preferably provided with reinforcing strips such as 29 and 30 so that 85 it will stand a maximum amount of rough usage to which such constructions are subjected. The upper strip 29 also serves as a stop for the edge of the cover when the cover is closed and also serves as a convenient anchorage for the latches and lock.

The case and the tray are preferably light in weight and may be made of aluminum, wood or fibre.

It will be seen that the tray provides space 95 not only for two sets of graded nut and cap screw wrenches but it also provides space for other miscellaneous articles and tools at the sides and ends. It will also be noted that when the tray is placed in the case there is 100 still room not only for the full tray but for other articles which can be placed on top of the tray, such articles, for instance, as overalls, waste, or cleaning material, etc.

Certain features of this invention are 105 broadly covered in my copending application Serial No. 4,408.

I claim:

1. A mechanic's tool tray having converging side walls and transverse partitions 110 forming two series of compartments graded in depth from the center toward opposite

ends of the tray, the deeper compartments near the center being also wider than shallower compartments near the ends and adapted to hold systematically two graded sets of wrenches.

2. A mechanic's tool tray as set forth in claim 1 having vertical slots in said side walls at the edges of some of said compartments to permit an instrument to be inserted 10 into said compartments.

3. A tool kit tray comprising side walls higher in the center than in the opposite ends, transverse partitions between said side walls graded in height, and other shorter 15 side walls spaced apart from the first-mentioned side walls and transverse partitions between adjacent side walls.

4. A tool kit tray having two sets of parallel walls, the walls of each set being 20 spaced apart at approximately equal dis-

tances throughout their length and the two sets converging toward each other at their outer ends, and transverse partitions between said sets varying in height so as to provide two oppositely disposed series of 25 compartments of graded depth and width with shallower compartments on the sides.

5. A tool kit tray having two sets of parallel walls, the walls of each set being spaced apart at approximately equal distances throughout their length and the two sets converging toward each other at their outer ends, transverse partitions between said sets varying in height so as to provide two oppositely disposed series of compartments of graded depth and width with shallower compartments on the sides, and a vertically sliding handle secured at the center. 30 35

CHARLES L. LAWRENCE.
